UNITED STATES PATENT OFFICE.

LEMON M. REED, OF CLEVELAND, OHIO, ASSIGNOR TO HATTIE E. GYNN, OF CLEVELAND, OHIO.

MIXING APPARATUS FOR MAKING CEMENTITIOUS PRODUCTS.

1,317,942.

Specification of Letters Patent.

Patented Oct. 7, 1919.

Application filed April 25, 1919. Serial No. 292,593.

To all whom it may concern:

Be it known that I, LEMON M. REED, a citizen of the United States, residing at Cleveland, in the county of Cuyahoga and 5 State of Ohio, have invented a new and useful Mixing Apparatus for Making Cementitious Products, of which the following is a specification.

This invention relates to improvements in 10 mixing apparatus for making cementitious products, and pertains more especially to improved apparatus for mixing dry sand and dry hydraulic cement and wetting or moistening the dry cementitious mixture.

15 One object of this invention is to produce mixing apparatus of the character indicated by which, without the use of meshed or foraminated screens, dry sand and dry hydraulic cement may be thoroughly mixed and 20 distributed over an open box or receptacle for receiving the resulting cementitious product.

Another object is to render said apparatus 25 highly efficient and reliable in the performance of its functions and simple and durable in construction.

Another object is to have said apparatus comprise simple and efficient means for wetting or moistening the hereinbefore mentioned mixture during its passage and in 30 proximity to the aforesaid receptacle.

With these objects in view, and to attain any other object hereinafter appearing, this invention consists in certain features of construction, and combinations and relative arrangements of parts, hereinafter described in 35 this specification, pointed out in the claims, and illustrated in the accompanying drawings.

40 In said drawings, Figure 1 is a vertical longitudinal section of apparatus embodying my invention. Fig. 2 is a vertical transverse section taken along the line 2—2, Fig. 1, looking in the direction indicated by the arrow. Fig. 3 is a vertical transverse section taken along the line 3—3, Fig. 1, looking in the direction indicated by the arrow. Fig. 3 is drawn on a larger scale than the preceding figures, and portions are broken 45 away in Fig. 3 to reduce the size of the drawing.

Referring to Fig. 1 of said drawings, 11 and 12 indicate two hoppers for receiving dry sand and dry hydraulic cement respectively. Said hoppers are adapted to dis-

charge downwardly and arranged side by side and supported from and rendered rigid with stationary framework 13 in any approved manner. Said framework is shown resting on the floor 15. Two laterally spaced substantially horizontal and substantially parallel rotary conveyers 17 and 18 are arranged under the outlet of the different hoppers 11 and 12 respectively. The conveyers 17 and 18 are operatively mounted on correspondingly arranged shafts 19 and 21 respectively which are supported from the framework 13 and operated in any approved manner, and each conveyer has peripheral chambers 20 spaced circumferentially 70 of the conveyer and arranged to communicate with and receive material from the outlet of the superimposed hopper during the rotation of said conveyer. Said shafts are of course rotated in the direction required to 75 rotate the conveyers 17 and 18 in the direction necessary to feed materials received from the hoppers into the space between the lower portions of the conveyers. Means for effecting the operation of said conveyers are 80 too well known in the art to require further description and illustration in this specification. Adjacent each conveyer (see Fig. 1) is a guard 23 which extends from the outlet of the hopper arranged above said conveyer 85 downwardly circumferentially of the inner side of the upper portion of and is arranged in close proximity to said conveyer. Each guard 23 is arranged and adapted to cover a chamber 20 of the conveyer circumferentially of which said guard extends, and said chamber does not discharge the contents thereof during the operation of the conveyer 90 until the chamber has begun to move below the lower end of said guard. The cement-conveyer 18 is shown as having twice as 95 many chambers 20 as the sand-conveyer 17, and each chamber of the sand-conveyer is shown as having over twice the capacity of a chamber of the cement-conveyer, and the relative operation of said conveyers is such as to feed cement and sand, in the desired proportion, into the space between the lower portions of the conveyers. Two guards 24 are located at the outer side of the different 100 conveyers respectively. Each guard 24 extends from the outlet of the adjacent hopper circumferentially of the adjacent conveyer and is arranged and adapted to cover a chamber 20 of said conveyer. Upon the 105 110

floor 15, below the conveyers 17 and 18, is an open box or receptacle 25, and said conveyers are arranged far enough above said receptacle to permit the arrangement, between said receptacle and said conveyers, of apparatus employed in mixing the sand and cement during the passage of said materials from said conveyers to said receptacle.

The mixing apparatus comprises a substantially vertically arranged metal casing 26 which is open at its upper and lower ends and arranged between the receptacle 25 and the conveyers 17 and 18. Preferably said casing is enlarged in thickness, as at 27, at its lower end and suspended by upright links 28 from brackets or members 29 which are rigid with and project from the hoppers 11 and 12 and are consequently rigid with the framework 13. At each side of said casing are two upright links 28 which are pivoted at their lower ends, as at 30, to said casing and pivoted at their upper ends, as at 31, to the link-supporting members 29. Each link 28 at each side of the casing 26 is arranged opposite a corresponding link at the opposite side of the casing, as shown in Fig. 2. The pivotal connections between the casing 26 and the links 28 and the pivotal members 31 connecting said links to the link-supporting members 29 are parallel with the conveyers 17 and 18. The casing 26 is therefore shown arranged and supported as required to render it capable of being reciprocated in a substantially horizontal plane. A crank-shaft 32 is supported from the top portion of the framework 13 at one end of said framework, and said shaft is parallel with the conveyers 17 and 18, and preferably a link 28 at each side of the casing 26 is operatively connected by a pitman 33 with a crank 34 of said shaft which is rotated in any approved manner, during the operation of the conveyers, to effect a rapid reciprocation of said casing. The framework 13 is provided with a pair of substantially horizontal and substantially parallel laterally spaced bars 36 which are arranged internally of the casing 26 and extend longitudinally of the travel of said casing. The bars 36 are supported from and rigid with brackets 37 with which the top portion of the framework 13 is provided. Said bars are spaced downwardly from the conveyers 17 and 18 and upwardly from the lower end of the casing 26, and the relative arrangement of the parts is such as to permit movement of said casing longitudinally of said bars in opposite directions alternately by the hereinbefore described operative connection of said casing with the crank-shaft 32. The brackets 37 at each end of the pair of bars 36 are tied together by bars 38 so as to render the bars 36 adequately rigid. The bars 36 are provided with a row of four inclined metal plates 39 arranged thereon inter-

nally of the casing 26, and said plates are rigid with and spaced and extend longitudinally of said bars. Adjacent plates 39 slope downwardly in the direction of opposite ends respectively of the bars 36 and are arranged to receive materials to be supplied from above and to be mixed during the reciprocation of said casing, and the two inner plates of said row of plates diverge upwardly. By the construction hereinbefore described it will be observed that each outer plate and the adjacent inner plate of said row of plates converge upwardly and that the bars 36 and the said plates are supported independently of the casing 26 and are stationary, being rigid with the framework 13. Means whereby the materials delivered by the conveyers 17 and 18 to the space between the lower portions of said conveyers are conducted or fed over and to and between the stationary plates 39 comprise two downwardly diverging inclined metal plates 40 supported from the casing 26. The end walls of said casing preferably do not extend upwardly as far as the bars 36, whereas the side walls of said casing extend above said bars and above the plates 40. The plates 40 are arranged over the bars 36 and meet at their upper ends and have flanges 41 secured to the casing 26 in any approved manner. The plates 39 of the bars 36 are therefore arranged to receive materials from the plates 40 during the reciprocation or actuation of the casing 26 longitudinally of said bars. Each plate 40 in the central position of the casing 26 (see Fig. 1) has its upper end under the central portion of the space between the lower portions of the conveyers 17 and 18 and over the space between the lower ends of the inner upwardly diverging plates 39, and has its lower end in position over the space between two adjacent upwardly converging plates 39. The relative arrangement of the parts is such that the stationary plates 39 are arranged wholly internally of the casing 26 in any position of the casing. Each plate of the row of plates 39 has a flange 42 which projects substantially vertically downwardly from the upper end of said plate and is arranged transversely of said row. The flanges 42 of adjacent upwardly converging plates 39 are helpful in guiding materials vertically downwardly through the space between said flanges. The plates 39 have flanges 43 secured to the casing 26 in any approved manner. Said casing is provided internally and below the stationary plates 39 with means for retarding the movement of materials from said plates and from the spaces between said plates to the lower end of the casing and for further mixing and distributing said materials during said movement, and said means comprise three vertically spaced substantially parallel rows 130

of inclined metal plates 45 arranged internally of and supported from and movable with the casing. The rows of plates 45 are arranged longitudinally of the bars 36, and 5 adjacent plates of each row of plates 45 slope downwardly in the direction of opposite ends respectively of said row. Adjacent downwardly converging plates of each row of plates 45 are spaced at their lower 10 ends. Adjacent upwardly converging plates of the upper row of adjacent rows of plates 45 extend into close proximity to each other and preferably meet at their upper ends and have their upper portions arranged over the 15 space between the lower ends of two adjacent downwardly converging plates of the lower row of said adjacent rows of plates.

Each of adjacent upwardly converging plates of each row of plates 45 is provided 20 at its upper end with a substantially vertically upwardly projecting flange 46 extending transversely of said row. The plates 45 have flanges 47 secured to the casing 26 in any approved manner. The flanges 46 of 25 adjacent upwardly converging plates of each row of plates 45 abut against each other and form a partition, and each partition thus formed at the top of the bottom row of plates 45 is substantially in line vertically 30 with a partition formed at the top of the top row of plates 45. Each partition formed by abutting flanges 46 is helpful in effecting a substantially equal distribution of materials to the plates diverging downwardly 35 from said partition.

Means for wetting or moistening the dry mixture of sand and hydraulic cement, upon the passage of said mixture from the plates of the bottom row of plates 45, comprise perforated pipes 48. Preferably the casing 26 is provided over the space between the lower 40 ends of adjacent downwardly converging plates of the bottom row of plates 45 with a substantially horizontal pipe 48 arranged 45 transversely of said row and supported by and movable with the casing 26 and (See Fig. 3) provided at its bottom with perforations 49 which are spaced at short intervals longitudinally of the pipe and arranged to discharge 50 downwardly into said space, and obviously as two adjacent downwardly converging plates 45 are arranged to discharge into said space the dry mixture fed to said space by said plates is wet or moistened by 55 water discharged from said pipe before said mixture can descend into the receptacle 25. The perforated pipes 48 are placed in open relation at the ends, by pipes 50 arranged externally of and longitudinally of the casing 26, with flexible tubes 51 which communicate with branches 52 of a water-supply pipe 53 having a valve 54 upon opening which water is supplied from said supply pipe through the branch-pipes 52, tubes 51 60 and pipes 50 to the pipes 48.

By the construction hereinbefore described it will be observed that the stationary plates 39 and the uppermost plates 40 constitute means whereby the dry materials requiring further mixing are delivered over and to 70 and between the plates of the top row of plates 45, that the intermediate and top rows of plates 45 constitute means between the row of pipes 48 and the row of stationary plates 39 for further agitating and mixing 75 said materials during their descent to the bottom row of plates 45, and that the last-mentioned plates constitute means whereby feeding of the dry mixture into the spaces under said pipes, and consequently into the 80 aqueous discharge from said pipes, is insured.

What I claim is—

1. In mixing apparatus, a movable casing which is open at its upper and lower ends 85 and adapted to be reciprocated in a substantially horizontal plane, means for reciprocating said casing, vertically spaced substantially horizontal rows of inclined plates arranged internally of and movable with the 90 casing, and means whereby materials are supplied over and to and between the plates of the top row of plates, adjacent plates of each row of plates sloping downwardly in the direction of opposite ends respectively 95 of said row, adjacent downwardly converging plates of each row of plates being spaced at their lower ends, adjacent downwardly diverging plates of the upper row of adjacent rows of plates meeting at their upper 100 ends and arranged over the space between the lower ends of two adjacent downwardly converging plates of the lower row of said adjacent rows, and adjacent downwardly diverging plates of each row of plates being 105 provided at their upper ends with substantially vertically upwardly projecting flanges forming a partition arranged transversely of said row.

2. In mixing apparatus, a movable casing open at its upper and lower ends and adapted to be reciprocated in a substantially horizontal plane, means for reciprocating said casing, three vertically spaced substantially horizontal rows of inclined plates arranged internally of and movable with said casing, and means whereby materials are supplied over and to and between the plates of the top row of plates, adjacent plates of each row of plates sloping downwardly in the direction of opposite ends respectively 110 of said row, adjacent downwardly converging plates of each row of plates being spaced at their lower ends, adjacent downwardly diverging plates of the upper row of adjacent rows of plates meeting at their upper 115 ends and arranged over the space between the lower ends of two adjacent downwardly converging plates of the lower row of said adjacent rows, and the joint formed between 120

125

adjacent downwardly diverging plates of the bottom row of plates being substantially in line vertically with the joint formed between two adjacent downwardly diverging plates of the top row of plates.

3. In mixing apparatus, a movable casing which is open at its upper and lower ends and adapted to be reciprocated in a substantially horizontal plane, a substantially horizontal row of stationary spaced inclined plates arranged internally of said casing and spaced upwardly from the lower end and supported independently of the casing, means for reciprocating said casing, means for conveying materials over and to and between the aforesaid plates, and means arranged internally of said casing and below said plates for retarding passage of said materials to the lower end of said casing from said plates and from the spaces between the plates.

4. In mixing apparatus, a movable casing which is open at its upper and lower ends and adapted to be reciprocated in a substantially horizontal plane, a row of spaced inclined plates which are spaced upwardly from the lower end and supported independently of said casing, means for reciprocating said casing, means for conveying materials over and to and between said plates, and means arranged internally of said casing and below said plates for retarding passage of materials to the lower end of the casing from said plates and from the spaces between the plates, each outer plate and the adjacent inner plate of the aforesaid row of plates sloping downwardly in the direction of opposite ends respectively of said row.

5. In mixing apparatus, a movable casing which is open at its upper and lower ends and adapted to be reciprocated in a substantially horizontal plane, a substantially horizontal row of spaced inclined plates which are spaced upwardly from the lower end and supported independently of said casing, means for reciprocating said casing, and means for conveying materials over and to and between said plates, means for retarding passage of said materials to the lower end of said casing from said plates and from the spaces between the plates, each outer plate and the adjacent inner plate sloping downwardly in the direction of opposite ends respectively of the row of plates, and each plate having a flange which projects substantially vertically downwardly

from the upper end of the plate and is arranged transversely of said row of plates.

6. In mixing apparatus, a movable casing which is open at its upper and lower ends, a pair of laterally spaced and substantially parallel bars arranged substantially horizontally internally of said casing and spaced upwardly from the lower end of the casing, two downwardly diverging inclined plates carried by said casing above said pair of bars and adapted to receive and conduct materials to be mixed and sloping downwardly toward opposite ends respectively of said bars, means arranged below said pair of bars and internally of said casing for retarding downward passage of materials between said pair of bars and the lower end of the casing, and means for actuating said casing longitudinally of said bars in opposite directions alternately, said bars being provided below the aforesaid plates with a row of inclined plates which are spaced and extend longitudinally of the bars, the first-mentioned plates being arranged over the central portion of said row of plates in the central position of the casing, and adjacent plates of said row of plates sloping downwardly in the direction of opposite ends respectively of the bars.

7. The combination, with a movable casing which is open at its upper and lower ends and adapted to be reciprocated in a substantially horizontal plane, means for reciprocating said casing, and a row of downwardly discharging and substantially horizontal spaced perforated pipes which are arranged internally of the lower end portion and transversely of and movable with the casing, of inclined plates arranged internally of said portion of the casing and adapted to receive a dry mixture of sand and cement and discharge said mixture into the discharge from said pipes, means internally of said casing between the row of pipes and the upper end of the casing for agitating and mixing materials fed into the upper end of the casing, and means for supplying water to said pipes.

In testimony whereof I sign the foregoing specification, in the presence of two witnesses.

LEMON M. REED.
